US00D809217S

(12) **United States Design Patent** (10) Patent No.: **US D809,217 S**
(45) Date of Patent: ** Jan. 30, 2018

(54) **FLEA COMB**

(71) Applicant: **T.F.H. PUBLICATIONS, INC.**,
Neptune City, NJ (US)

(72) Inventors: **Glen S. Axelrod**, Colts Neck, NJ (US);
Ajay Gajria, Maharashtra (IN)

(73) Assignee: **T.F.H. PUBLICATIONS, INC.**,
Neptune City, NJ (US)

(**) Term: **15 Years**

(21) Appl. No.: **29/555,509**

(22) Filed: **Feb. 23, 2016**

(51) LOC (11) Cl. **30-99**

(52) U.S. Cl.

USPC **D30/159**

CLAIM

We claim the ornamental design for a flea comb, as shown and described.

DESCRIPTION

FIG. 1 is a perspective view of a flea comb of the present invention;

FIG. 2 is a back view of the flea comb of FIG. 1;

FIG. 3 is a front view of the flea comb of FIG. 1;

FIG. 4 is a left side view of the flea comb of FIG. 1, the right side view being a mirror image thereof;

FIG. 5 is a top end view of the flea comb of FIG. 1; and,

FIG. 6 is a bottom end view of the flea comb of FIG. 1.

1 Claim, 4 Drawing Sheets
